UNITED STATES PATENT OFFICE.

HOLLACE HARRISON BAIN, OF SHREVEPORT, LOUISIANA.

COLLAPSIBLE RECEPTACLE.

1,412,912.

Specification of Letters Patent. Patented Apr. 18, 1922.

Application filed July 18, 1919. Serial No. 311,739.

To all whom it may concern:

Be it known that I, HOLLACE HARRISON BAIN, a citizen of the United States, and a resident of Shreveport, in the parish of Caddo and State of Louisiana, have invented certain new and useful Improvements in Collapsible Receptacles, of which the following is a specification.

This invention relates to receptacles, containers or tanks, to be used for storing or containing all kinds of liquids, for grain, cotton and cotton seed, silage, etc., and particularly to containers of sheet metal.

The primary object of my invention is to provide a container or tank which is formed in a number of sections and which may be collapsed or nested one within the other so as to economize space in transportation, and which when they have reached their destination may be readily erected to form the full sized tank.

A further object is to provide a tank, receptacle or container of the character described which can be readily taken apart, moved to a new location, and again set up.

A further object is to form a friction joint between the sections of the container when the several sections are set up, which will permit ready assembling of the container or tank by unskilled labor, but which will hold the several sections firmly in their assembled position.

A further object is to provide for sealing the joint by cement or like material and to provide a seat on a lower section of the container to support the upper section and assist in holding the upper part of the lower section in true circular form.

Another object is to provide means for exerting compressive force on the joint to thereby hold the parts in firm engagement.

Other objects will appear in the course of the following description.

My invention is shown in the accompanying drawings, wherein:

Figure 1 is a side elevation of my collapsible tank, container or receptacle assembled,

Figure 2 is a vertical section of the parts collapsed, the innermost section being in elevation,

Figure 3 is a top plan view of the assembled tank,

Figure 4 is an enlarged detail vertical

section through the joint between two sections,

Figure 5 is a plan view of the saddle receiving the ends of the clamping rod,

Figure 6 is a side elevation of the same, and

Figure 7 is a section on line 7—7 of Figure 6.

As illustrated in Figures 1 to 3, my container, receptacle or tank is composed of three sections A, B and C, the sections having such different diameters the three sections may be nested or collapsed one within the other. Of course less or more than three sections may be used, and the drawing is purely illustrative in this regard.

The lower section A has a bottom 10 and a side wall 11. Adjacent its upper end or rim the side wall is formed with a circumferentially inwardly extending bead 12, which is relatively deep and above this with 75 a similar but shallow circumferential groove 13 or bead and above this with a vertical rim 14.

That end which forms the base of the section B, which is to engage with the upper end of section A, is outwardly flared at 15, as shown in Fig. 4, and has a skirt 15^a extending over an annular channeled member 16, which is held between the flare 15 and a horizontal flange on skirt 15^a. The opposite end or rim is formed to provide the beads 12 and 13. The body of the section B has a diameter slightly smaller than the interior diameter of section A, at bead 12.

Section C has a diameter for the greater portion of its length slightly less than the diameter of section B, at bead 12, but is outwardly flared at 15^b and formed with a channeled rim similar to channel iron on member 16. Section C is considered in the drawings to be the top section of a three-piece tank or container and may be closed at its end 17, or provided with a small opening closed by a cover or plug, or this section may be open at its top. This will depend on the purpose for which the tank or container is used.

Under all circumstances there will be a bottom section A, a top section C, and one or more intermediate sections, each section being slightly smaller than the section next below except at 15 and 16.

In assembling the sections, section B is to

be withdrawn from its nested position, as in Figure 2, inverted and then disposed upon section A, as shown in Figures 1 and 4, so that the channelled rim 16 of B, seats 5 upon the bead 12. Then a hoop or annular band 18 is disposed in bead 13. This band is screw-threaded at its ends and passed through two abutments 20 on a curved clip or saddle 19. This clip is very thin at its 10 extremities and the inner face of the clip conforms to the shape of bead 13. The straining band 18 of course carries nuts 21 whereby the same may be tightened.

After the section B has been disposed with 15 its rim 16 seated on bead 12, then the nuts 21 are turned up gradually and the hoop is continuously and evenly hammered until gradually the bead 13 and rim 14 are pressed inward until the joint assumes the position 20 shown in Figure 4 when the joint becomes a friction joint. Then cement 22 of any suitable character is poured into the annular pocket formed at the joint and the joint is made liquid and air tight.

25 The succeeding section C, or sections, are put in place in the same manner until the tank or receptacle is completed.

It will be seen that I have provided a 30 collapsible or knockdown receptacle, tank or bin, wherein the sections can be nested for transportation or storage, and that I have provided for connecting these sections, a friction or compression joint so constructed that the sections may be put together by un- 35 skilled labor, and further that I have provided an annular gutter or groove to hold cement or other sealing material so formed that the cement will stay in place by gravity; and not run down the sides of the structure 40 and mar its looks.

Below this point I provide a ledge or seat 45 formed by bead 12, which is swaged in or attached to the upper end of the section upon which the lower end of the adjacent upper section rests. This seat assists in holding the lower end of the next upper section in a true circle and in a true horizontal plane, and greatly facilitates the erection of the receptacle.

50 The annular channel ring 16 is of heavier material or greater thickness than the rest of the section and withstands the compression exerted by the compression hoop or tie 18.

55 While I have illustrated a particular form of joint, which I have found to be particularly effective, yet I do not wish to be limited to this as the principle may be embodied in other forms.

60 Bins, tanks, containers, receptacles, etc., may be formed as I have described and are adapted to hold liquids, grain, cotton and cotton seed, silage, etc., but are especially adapted for water tanks to rest on the 65 ground, platform or tower.

I claim:

1. A receptacle of the character described, consisting of a plurality of sections adapted to be nested one within the other, or disposed in longitudinally consecutive relation, the 70 base of one section supporting an annular channelled member, and the rim of an adjacent section having an annular beaded projecting portion fitting thereon, and an expandable and contractible hoop adapted to 75 force the said beaded portion into said channelled member.

2. A receptacle of the character described, comprising a plurality of sections adapted to be nested one within the other, or disposed 80 in longitudinally consecutive relation, the rim of a lower section having an inwardly projecting annular bead, and the base of the superjacent section having an annular skirt supporting an annular channel iron confronting the bead when the sections are disposed in consecutive relation, a contractible hoop disposed in the bead whereby the beaded rim and skirt may be forced into the channel iron, and sealing material filling 85 the space between the rim and channel.

3. A receptacle of the character described, comprising a plurality of sections adapted to be nested one within the other, or disposed 90 in longitudinally consecutive relation, the rim of a lower section having an inwardly extending annular bead, and the base of the superjacent section having an annular channel confronting the bead when the sections are disposed in consecutive relation, and a 100 straining band disposed in the bead whereby the beaded rim may be forced into the channel, the subjacent section having an inwardly projecting annular shoulder for supporting the base of the superjacent section.

4. A receptacle of the character described, comprising a plurality of sections adapted to be nested one within the other, or disposed 105 in longitudinally consecutive relation, the rim of a lower section having an inwardly projecting annular bead, and the base of the superjacent section being flared outwardly, an annular skirt depending from the flare and supporting internally an annular channel iron confronting the bead when the sections are disposed in consecutive relation, and a contractible hoop disposed in the bead whereby the beaded rim and skirt may be forced into the channel, the subjacent section having an inwardly projecting annular bead below the first named bead and deeper 115 than the latter, forming a seat for the base of the superjacent section.

5. A receptacle of the character described, comprising a plurality of sections adapted 120 to be nested or disposed in longitudinally consecutive relation, the rim of one section having a relatively shallow inwardly projecting bead and below it a relatively deep annular bead, the superjacent section having 125

for the greater portion of its length a diameter less than the internal diameter of the subjacent section at said second named bead, the lower end of the superjacent section flaring outward and being formed with a relatively strong annular channelled member, adapted to rest on the second named

bead and confront the first named bead, a contractible hoop seating in the first named bead whereby the said bead may be forced 10 into the channel, and sealing material disposed in the space between the bead and channel.

HOLLACE HARRISON BAIN.
